UNITED STATES PATENT OFFICE.

ROBERT MUIR, OF WATERTOWN, MASSACHUSETTS, ASSIGNOR TO HOOD RUBBER COMPANY, OF WATERTOWN, MASSACHUSETTS, A CORPORATION OF MASSACHUSETTS.

DESIGN FOR A VEHICLE TIRE.

60,732.

Specification for Design.

Patented Mar. 28, 1922.

Application filed June 10, 1921. Serial No. 476,561. Term of patent 7 years.

To all whom it may concern:

Be it known that I, ROBERT MUIR, a citizen of the United States, residing at Watertown, in the county of Middlesex and Commonwealth of Massachusetts, have invented a new, original, and ornamental Design for a Vehicle Tire, of which the following is a specification, reference being had to the accompanying drawing, forming part thereof.

In this drawing Fig. 1 is a developed plan

view of a sufficient portion of a tire to illustrate my new design.

Fig. 2 is a side elevation, and

Fig. 3 a transverse section on line 3, 3 of Fig. 2.

I claim:

The ornamental design for a vehicle tire as shown.

ROBERT MUIR.
